UNITED STATES PATENT OFFICE.

CHARLES F. STODDARD, OF BOSTON, MASSACHUSETTS, ASSIGNOR TO AMERICAN PNEUMATIC SERVICE COMPANY, OF DOVER, DELAWARE, A CORPORATION OF DELAWARE.

PNEUMATIC-DESPATCH APPARATUS.

No. 923,458.

Specification of Letters Patent.

Patented June 1, 1909.

Application filed January 9, 1904. Serial No. 188,379.

To all whom it may concern:

Be it known that I, CHARLES F. STODDARD, of Boston, in the county of Suffolk and State of Massachusetts, have invented 5 certain new and useful Improvements in Pneumatic-Despatch Apparatus, of which the following is a specification.

My invention relates to new and useful improvements in terminals for pneumatic 10 despatch apparatus, and especially to such apparatus wherein large carriers are used for the transmission of mail matter and merchandise.

The object of my invention is to produce 15 an apparatus simple in construction and efficient in operation.

My invention consists of certain novel features hereinafter described and particularly pointed out in the claims.

20 In the accompanying drawings which illustrate a construction embodying my invention, Figure 1 is a side elevation of the terminal. Fig. 2 is a longitudinal section of the controlling valve in its normal position. Fig. 3 is a longitudinal section of the auxiliary valve in its normal position. Fig. 4 is a longitudinal section of the controlling valve in a position opposite to that shown in Fig. 2. Fig. 5 is a longitudinal section 25 of the auxiliary valve shown in a position opposite to that shown in Fig. 3.

Like letters of reference refer to like parts throughout the several views.

The transmission tube A is located in 35 alinement with the compression chamber A³ of the terminal, and has a slotted casing A' through which pressure passes into the exhaust tube A². The front end of the compression chamber A³ is normally closed to 40 the atmosphere by the gate A⁴ which is connected to the piston A⁵ of the cylinder A⁷ by the piston rod A⁶.

A⁸ is a receiving table and A⁹ a suitable 45 buffer to stop the carriers at the end of the table. The main controlling valve C is supplied with air under pressure by the pipe B⁶ and exhausts through the pipe B⁷. The auxiliary cylinder C' is connected to the controlling valve C. The piston C² of the auxiliary cylinder C' is connected to the piston rod C³ passing through the stuffing

box S and to which are also connected the pistons C⁴ C⁵ of the controlling valve C. One side of the cylinder C' is connected with the front end of the compression chamber 55 A³ by the pipe B² and the other side of the cylinder C' is connected with the auxiliary valve B⁴ by the pipe B³. The auxiliary valve B⁴ is also connected with the supply pipe B⁶ by the pipe B⁵. The finger F which 60 operates the piston rod F² is pivoted at D and rests normally on the pin D'.

L⁸ is the floor line and L, L', L² are legs supporting the table on the forward part of the terminal.

P P' are ports of the main cylinder and P² P³ are the supply ports of the controlling valve; P⁴ is the exhaust port of the controlling valve.

P⁵ and P⁶ are respectively connected to 70 the ports P' and P by the pipes B' and B.

P⁷ and P⁸ are ports in the auxiliary valve to which are connected the pipes B³ B⁵ respectively and P⁹ is an atmospheric port located in the upper part of the auxiliary 75 valve B⁴.

S' is a spring operating the plunger S² of the auxiliary valve B⁴.

F³ and F⁴ are the pistons of the plunger S².

The operation is as follows: The carrier coming in to the terminal from the transmission tube A passes through the casing A' into the compression chamber A³ where it is stopped by compressing the air in 85 front of it against the gate A⁴. This compressed air in front of the carrier passes through the pipe B² into the cylinder C' forcing the piston C² into the position shown in Fig. 4 thereby opening the port P⁵ to the pressure which comes into the controlling valve C through the port P², and opening the port P' to the atmosphere through the port P⁴, this being controlled by the pistons 90 C⁴ C⁵. When the piston C² moves from 95 the position shown in Fig. 2 to the position shown in Fig. 4, the air in front of it passes out through the pipe B³ and the ports P⁷ and P⁹ of the auxiliary valve B⁴. The pressure then flows through the pipe B' through 100 the port P' to the under side of the piston A⁵ of the cylinder A⁷ and forces the piston

2
to the top of the cylinder, the air above the piston passing out through the port P and pipe B and port P^6 and port P^4 into the atmosphere. There is just enough pressure 5 in the transmission tube A to blow the carrier out on to the table A^8 against the buffer A^9 . As the carrier passes from under the gate A^4 it engages the finger F raising it into the position shown in Fig. 5, and this 10 finger F in turn raises the plunger S^2 in the cylinder B^4 so that the port P^8 is in communication with the port P^7 allowing the pressure which comes from the supply pipe B^6 through the pipe B^5 to flow through the 15 pipe B^3 into the cylinder C' thereby forcing the piston C^2 back into the position shown in Fig. 2. When the plunger S^2 moves from the position shown in Fig. 3 into the position shown in Fig. 5 it checks 20 communication between the port P^7 and the port P^9 which in turn communicates with the atmosphere. This operation opens the port P^5 to the atmosphere through the port P^4 , and the port P^6 to the pressure which 25 comes through the port P^3 , and these ports in turn open the lower end of the cylinder A^7 to the atmosphere and the upper side to the pressure which forces the piston A^5 into the position shown in Fig. 1, thereby closing 30 the transmission tube A^3 by the gate A^4 , which puts the terminal into its normal position ready to receive another carrier.

The ports P^2 , P^3 receive their air pressure supply from any suitable source from the 35 pipe B^6 and the port P^1 exhausts to the atmosphere through the exhaust pipe B^7 .

Having thus described the nature of my invention and set forth a construction embodying the same what I claim as new and 40 desire to secure by Letters Patent of the United States is:

1. In apparatus of the character described, a receiving terminal for the carrier, a gate in said terminal for compressing the air in 45 front of the carrier, pneumatically operated means communicating with a source of compressed air for moving said gate, a valve controlling the communication between the pneumatically operated means 50 and its source of compressed air, a piston for actuating said valve, a cylinder containing said piston communicating on one side of the piston with said terminal to permit the air compressed therein by the carrier to move the piston in one direction and said cylinder communicating on the other side of the piston with an air-supply separate from that compressed by the carrier to move the piston in the opposite direction, and 55 means for controlling the communication leading to the cylinder from the air-supply separate from that compressed by the carrier.

2. In apparatus of the character de- 60 scribed, a receiving terminal for the car-

rier, a gate in said terminal for compressing the air in front of the carrier, pneumatically operated means communicating with a source of compressed air for moving said gate, a valve controlling the communication between the pneumatically operated means and its source of compressed air, a piston actuating said valve, a cylinder containing said piston communicating on one side of the piston with said terminal 70 to permit the air compressed therein by the carrier to move the piston in one direction and said cylinder communicating on the other side of the piston with an air-supply separate from that compressed by the carrier to move the piston in the opposite direction, and means actuated by the carrier after the latter has passed the gate for controlling the communication leading to the cylinder from the air-supply separate from 80 that compressed by the carrier. 85

3. In apparatus of the character described, a receiving terminal for the carrier, a gate in said terminal for compressing the air in front of the carrier, pneumatically 90 driven means communicating with a source of compressed air for moving said gate, a valve controlling the communication between the pneumatically driven means and its source of compressed air, pneumatically 95 operated mechanism actuated by the air compressed by the carrier to move said valve in one direction to open the gate and said pneumatically operated mechanism actuated by the direct pressure of compressed 100 air from a source separate from that compressed by the carrier to move said valve in the opposite direction to close the gate and means actuated by the carrier after the latter has passed the gate for controlling the 105 direct pressure of compressed air to said pneumatically operated mechanism from a source separate from that compressed by the carrier.

4. In apparatus of the character de- 110 scribed, a receiving terminal for the car- rier, a gate in said terminal for compressing the air in front of the carrier, a separate source of compressed air, pneumatically 115 driven means for opening and closing said gate, a communication between said separate source of compressed air and said pneumatically driven means, a valve controlling said communication, valve-actuating mechanism operated by fluid-pressure for moving 120 said valve, a communication admitting air compressed in the terminal by the carrier to said valve-actuating mechanism to operate the latter to move said valve to open said gate, a communication admitting air 125 from said separate source of compressed air to act directly upon said valve-actuating mechanism to move said valve to close said gate, an auxiliary valve controlling said communication between the separate source 130

of compressed air and the valve-actuating mechanism, and a finger for operating said auxiliary valve located beyond the gate so as to be struck by the carrier after the latter 5 has passed the gate.

In testimony whereof, I have signed my name to this specification in the presence of

two subscribing witnesses, this 21st day of December A. D. 1903.

CHARLES F. STODDARD.
